CATALYTIC HYDROCRACKING OF HYDROCARBONS WITH THE USE OF HALOGEN AND SULFUR ACTIVATORSReese A. Peck, Fishkill, Donald A. Messing, Glenham, and Edward T. Child, Brinckerhoff, N.Y., assignors to Texaco Inc., New York, N.Y., a corporation of Delaware
No Drawing. Filed Oct. 16, 1964, Ser. No. 404,498
4 Claims. (Cl. 208—111)

This invention relates to the conversion of hydrocarbons. More particularly it is concerned with the conversion of hydrocarbons in the presence of hydrogen to lighter hydrocarbons. In one of its most specific aspects it is concerned with the conversion of a nitrogen containing hydrocarbon feed stock boiling approximately in the kerosine-gas oil range in the presence of hydrogen and a cracking catalyst into hydrocarbons boiling in the naphtha-kerosine range.

Hydrocracking, previously known as destructive hydrogenation, has come into commercial prominence recently in the refining of petroleum hydrocarbons. In the hydrocracking process various reactions take place such as the cleaving of long straight carbon chains, the saturation of aromatic rings with subsequent rupture of the cycloparaffinic structure, the isomerization of paraffinic compounds into isoparaffinic compounds and the dealkylation of alkyl aromatics. Ordinarily, the charge to a hydrocracking unit will comprise hydrocarbons boiling above the range of the desired product. For example, if a motor fuel is desired, the charge to the hydrocracking unit will have an initial boiling point of about 400—450° F. whereas if the desired products are motor fuels and jet fuels, then the charge to the hydrocracking unit will have an initial boiling point of 550—600° F. Advantageously, charge stocks such as straight run kerosine and gas oil stocks obtained by the distillation of crudes and from catalytic cracking, vacuum gas oil and light distillates obtained from coal and shale may be charged to the hydrocracking unit. Ordinarily, product boiling above the desired end point is recycled to the hydrocracking unit.

Hydrocracking is preferably carried out in the presence of a catalyst which generally contains two components, a hydrogenating component and cracking component. Numerous hydrogenating components have been disclosed in the prior art such as Group VIII metals for example platinum, palladium and nickel and the oxides and sulfides of molybdenum, nickel, tungsten, and cobalt, and the like or mixtures thereof. The hydrogenating component is supported on a cracking base which advantageously is acidic in nature. Such bases comprise refractory oxides of one or more elements of Groups II, III, and IV of the Periodic Table. Suitable cracking supports include silica-magnesia, silica-alumina, silica-alumina-zirconia and the like. Synthetic and natural zeolites are also satisfactory in this respect. In some instances, the cracking support may be activated by treatment with an inorganic acid such as hydrofluoric acid or hydrochloric acid.

The present invention is particularly but not solely concerned with the use of catalysts comprising as the hydrogenating component the oxide or sulfide of cobalt and/or nickel supported on a silica-alumina cracking base having a high silica content. While these catalysts are eminently suitable for hydrocracking of various petroleum charge stocks, they are subject to an acute loss of catalyst activity when the charge stock contains even relatively small amounts of nitrogen.

As a measure of the catalyst activity it is customary to institute a hydrocracking reaction and conduct the process at certain conditions of temperature, pressure,

2

space velocity and hydrogen rate to obtain and maintain a predetermined conversion of the charge into material having a particular end boiling point. As the reaction proceeds, the catalyst is subject to loss in activity and, to compensate for the reduced activity, the temperature in the catalytic zone is increased to maintain the constant conversion rate. This increase in temperature necessary to maintain the desired conversion is called the aging rate. For example, it has been found that in a particular run when the charge contained 10 p.p.m. nitrogen, the aging rate was 24° F. per 100 hours. That is, in order to maintain the desired rate of conversion, it was necessary while keeping the other reaction conditions constant to raise the temperature of the catalytic zone an average of 24° F. over each 100 hour period. In the treatment of a similar charge containing only 3 p.p.m. nitrogen the aging rate was 7° F. per 100 hours and with a charge containing 1 p.p.m. nitrogen the aging rate was 2.4° F. per 100 hours.

When hydrocracking to produce a high octane motor fuel, the reactions which result in the desired type of product are inhibited after the temperature in the hydrocracking unit has reached about 750° F. It therefore becomes apparent that a charge stock which contains even as much as 10 p.p.m. nitrogen produces an undesirably rapid decline in catalyst activity. As a result a charge stock destined for treatment in a hydrocracking unit either must be subjected to rather severe preliminary treatment for nitrogen removal or the process may pay an excessive economic penalty by way of frequent catalyst regeneration and reactivation.

Reaction conditions within the hydrocracking unit generally include a temperature range of about 450—800° F. although a temperature of from 500 to about 750° F. is preferred. Pressures usually range from about 500 to 10,000 p.s.i.g. or higher, a preferred range being from 1000 to 3000 p.s.i.g. The hydrogen containing gas rate may range from 1000 to 20,000 s.c.f.b. (standard cubic feet per barrel) of normally liquid charge. Preferred hydrogen rates are from about 3000 to 8000 s.c.f.b. In this respect the term hydrogen includes impure hydrogen, such as a gas containing at least 70% hydrogen. Preferably, the space velocity, that is, volumes of liquid charge per volume of catalyst per hour will be between 0.5 and 3 although rates ranging from 0.1 to 10 may be used.

It is an object of the present invention to increase the activity of a hydrocracking catalyst. Another object is to prolong the life of a hydrocracking catalyst. Another object of the invention is to permit the use of nitrogen containing charge stocks in a hydrocracking operation. A still further object is to accomplish greater conversion into hydrocracking products at lower temperatures. These and other objects will be obvious to those skilled in the art from the following disclosure.

According to the present invention the hydrocracking is carried out in the presence of a halogen-containing compound and a sulfur-containing compound. These compounds may be introduced separately into the reactor or may be introduced into the reactor as a vapor in admixture with the hydrogen or as a component of the hydrocarbon charge stock. Preferably the halogen is in the form of an organic compound but any compound which is convertible to hydrogen halide under the reaction conditions is satisfactory. Suitable halogen containing compounds include alkyl and aryl halides such as chloroform, carbon tetrachloride, dichloroethane, chlorobenzene and the like. Preferably an organic compound having a high ratio of chlorine to carbon is selected.

The sulfur may be introduced in the form of H_2S or in the form of an organic sulfur-containing compound such as carbon disulfide, tertiary-butyl disulfide, lower

Ikyl mercaptans such as methyl mercaptan and ethyl mercaptan or other compounds convertible to H_2S under reaction conditions.

To be effective sulfur should be present in the reaction zone in an amount of at least 50 p.p.m. preferably between about 100 and 2000 p.p.m. by weight based on the hydrocarbon charge to the hydrocracking zone. However, when the charge contains more than 5 p.p.m. nitrogen, high concentrations of sulfur have no appreciable effect on the life of the catalyst unless halide is also present.

Advantageously, when the charge contains more than about 5 p.p.m. nitrogen the halogen content is maintained at a level such that the halogen:nitrogen atomic ratio is at least 1 and not more than about 80 and preferably is between about 20 and 70.

Example 1

In this example a charge stock containing varying amounts of nitrogen is hydrocracked at a temperature of 650° F., a pressure of 1500 p.s.i.g., a hydrogen rate of 15,000 s.c.f. per barrel over a NiO , S_2O , Al_2O_3 catalyst at a space velocity of 1.0 v./v./hr.

The results in Table 1 show the effect of the increasing nitrogen concentration on the aging rate of the catalyst.

TABLE 1

Nitrogen content of feed (p.p.m.):	Aging rate (° F./100 hrs.)
1	1.7
3	6.6
5	11.0
10	22.2
15	35

Example 2

In this example, a cycle gas oil (boiling range 430–640° F.) obtained from a fluidized catalytic cracking unit and containing 15 p.p.m. nitrogen and 20 p.p.m. sulfur is hydrocracked over a catalyst comprising NiO (5%) and Pt (0.125%) on silica-alumina at a temperature of 630–720° F., a pressure of 1500 p.s.i.g., a space velocity of 1.0 v./v./hr., and a hydrogen rate of 15,000 s.c.f. per barrel with varying amounts of 1,1-dichloroethane and n-butyl disulfide being added to contribute different amounts of halogen and sulfur to the reaction zone.

TABLE 2

Cl content (p.p.m.)	S content (p.p.m.)	Aging rate (° F./100 hrs.)
1,785	20	35
1,210	20	35
	1,320	3
	2,400	35

The data set forth in Table 2 show that in the case of a charge stock having a nitrogen content of 15 p.p.m., added halogen in conjunction with less than 50 p.p.m. sulfur, and added sulfur with no added halogen, does not improve the rapid aging rate but that when sulfur in excess of 50 p.p.m. in conjunction with added halogen is used, the aging rate of the catalyst is equivalent to that when there is not more than about 2 p.p.m. nitrogen in the charge. It is also to be noted from this example that sulfur in excess of 2000 p.p.m. in the absence of added halogen has no effect in improving the aging rate of the catalyst.

Example 3

In this example, a gas oil, mildly catalytically treated for sulfur and nitrogen removal, obtained from the atmospheric distillation of Southern Louisiana crude and containing 20 p.p.m. nitrogen and 40 p.p.m. sulfur is hydrocracked over a catalyst containing 5.7% NiO on a silica-alumina cracking base at 620–750° F., 1500 p.s.i.g., 1.0 v./v./hr. and 6000 s.c.f. hydrogen per barrel of charge. Halogen in the form of chlorobenzene and sulfur in the form of tertiary-butyl disulfide is added in varying amounts

to the charge. The results are shown in the following table.

TABLE 3

Cl content (p.p.m.)	Sulfur content (p.p.m.)	Aging rate (° F./100 hrs.)
1,500	40	50
	40	50
	140	50
1,500	140	4

This example shows that using a feed stock having a nitrogen content of 20 p.p.m., a sulfur content of 40 p.p.m. in the charge is insufficient alone to produce a low aging rate in the catalyst and also that halogen without added sulfur does not produce a low aging rate. However, when the sulfur content of the catalyst is at least 50 p.p.m. specifically in this example 140 p.p.m. and halogen is also added then the aging rate is greatly improved.

Example 4

This example shows the varying effect of different chlorine:nitrogen atomic ratios on the catalyst aging rate using gas oil charge stocks having a sulfur content of 60 p.p.m. and 10 and 15 p.p.m. nitrogen respectively under constant reaction conditions, only the temperatures being varied to maintain 40% conversion.

TABLE 4

N, p.p.m. in charge	Atomic Ratio, Cl:N	Catalyst aging rate, ° F./100 hrs.
15	62	1.2
15	32	2.5
15	17	3.8
15	—	35
10	99	0.4
10	48	0.9
10	25	2.2
10	—	22.2

The data in Table 4 show that with a charge containing 60 p.p.m. sulfur and 10 or 15 p.p.m. nitrogen, the catalyst aging rate is rapid but is slowed considerably with the addition of halogen.

The advantages of the present invention are not restricted to the treatment of charge stocks containing 5 or more p.p.m. combined nitrogen. The following example shows the improvements obtained when the invention is applied to a charge stock containing 1 p.p.m. nitrogen.

Example 5

In this example two charge stocks A and B are used, A containing 1 p.p.m. nitrogen with B substantially identical to A except for a nitrogen content of 15 p.p.m. Charge stock B is first hydrocracked under the conditions set forth in Example 3 and after determination of the aging rate charge stock A is substituted as charge to the reaction zone. The only effect in this instance is shown by a reduction in the aging rate. In an additional run charge stock B with halogen and sulfur added as indicated below is hydrocracked for a period of time sufficient to determine the aging rate after which charge A is substituted. However, in this case there is no appreciable change in the aging rate but there is an increase of approximately 35% in the conversion.

TABLE 5

Charge	Dichloroethane (p.p.m.)	t-Butyl disulfide (p.p.m.)	Aging rate (° F./100 hrs.)	Percent conversion
B	—	—	27	40
A	890	1,780	1.2	40
B	890	1,780	1.7	75
A	890	1,780	1.2	75

From a consideration of the runs made with charge stock A our experience indicates that, when sulfur and halogen are added to a low-nitrogen charge, it is possible to operate at 40° F. lower and still get the yield obtained when no sulfur and halogen is added.

Advantageously, the halogen is recovered from the reaction zone effluent and may be recycled to the reaction zone as for example by thermally decomposing the ammonium chloride recovered as a precipitate from the hydrocracking product to produce ammonia and hydrogen chloride, scrubbing the gaseous mixture to remove ammonia and recycling the hydrogen chloride to the hydrocracking zone.

Obviously, many modifications and variations of the invention as hereinbefore set forth may be made without departing from the spirit and scope thereof, and therefore, only such limitations should be imposed as are indicated in the appended claims.

We claim:

1. In a process in which a hydrocarbon charge stock containing more than 5 p.p.m. nitrogen and boiling in the gas oil range is contacted with a hydrocracking catalyst under hydrocracking conditions and in which the

catalyst is subjected to a loss in activity, the improvement which comprises reducing the rate of loss of activity of the catalyst by conducting said hydrocracking in the presence of a halogen compound and a sulfur compound present in an amount sufficient to supply at least 60 p.p.m. sulfur by weight based on the hydrocarbon charge, the halogen to nitrogen atomic ratio being between 17 and 99.

2. The process of claim 1 in which the halogen is chlorine.

3. The process of claim 1 in which the charge stock contains at least 10 p.p.m. nitrogen.

4. The process of claim 1 in which the halogen is supplied in the form of 1,1-dichloroethane.
